17 Claims. (Cl. 153—1)

1

This invention relates to apparatus and methods for forming or shaping cylindrical articles, such as bands, ferrules, tubings, and the like, of metal or other formable material, in connection with the making or assembly thereof.

It is an object of the invention to provide improved means and methods for forming and shaping articles of the type defined.

More specifically stated, it is an object of the invention to provide, in the forming and shaping of articles of the type stated, improved means for gripping and supporting the articles during the forming operation, improved and rapidly operable means for shaping the articles, and improved control devices for controlling the action of the gripping and shaping means.

A further object of the invention is to provide improved means and methods for attaching ferrules or fittings to hose and tubings.

A still further object is to provide an improved end connection for hose and metal tubing.

Various other objects, advantages and features of the invention will be apparent from the following specification when taken in connection with the accompanying drawings wherein a preferred embodiment of the invention is set forth for purposes of illustration.

In the drawings, wherein like reference numerals refer to like parts throughout:

Fig. 1 is a top assembly view, partly in plan section, of a ferrule attaching machine constructed in accordance with and embodying the principles of the invention, said view being taken substantially as indicated by the line 1—1 of Fig. 2;

Fig. 2 is a rear view of the machine illustrated in Fig. 1, taken as indicated by the line 2—2 thereof;

Fig. 3 is a front view of the forming head, partly in section, and taken as indicated by the line 3—3 of Fig. 4;

Fig. 4 is a vertical longitudinal section through the forming head, on the line 4—4 of Fig. 3;

Fig. 5 is a detail section, more particularly illustrating one of the guide tracks for the forming tool holder;

Fig. 6 is a detail section, on the line 6—6 of Figs. 2 and 4, of the shifting yoke for operating the forming tool;

Fig. 7 is an exploded detail view of certain of the parts illustrated in Fig. 6;

Figs. 8 and 9 are exploded views, respectively, illustrating various parts of the forming head;

Fig. 10 is a detail perspective view of the man-

2

drel forming a part of the support and gripping means for the work piece;

Fig. 11 is a longitudinal sectional view showing the work piece support means or chuck in one position of adjustment;

Fig. 12 is a sectional view on the line 12—12 of Fig. 11;

Fig. 13 is a view similar to Fig. 11 but showing the support chuck in a different position of adjustment;

Figs. 14 and 15 are sectional views taken on the lines 14—14 and 15—15, respectively, of Fig. 13;

Fig. 16 is a detail perspective view of one of the gripping jaws of the work piece support chuck;

Figs. 17, 18 and 19 are views illustrating successive steps in the operation of securing the ferrule onto the end of the hose or tubing;

Fig. 20 is a horizontal sectional view through the central rear portion of the machine taken as indicated on the line 20—20 of Fig. 21, and illustrating the action of certain of the control devices;

Fig. 21 is a vertical longitudinal sectional view through the mechanism of Fig. 20, and taken as indicated on the line 21—21 of Fig. 20 and Fig. 1;

Fig. 22 is a transverse vertical sectional view through the control mechanism taken on the line 22—22 of Fig. 1;

Figs. 23, 24 and 25 are transverse sectional views of the parts illustrated in Fig. 21 and taken as indicated, respectively, on the lines 23—23, 24—24 and 25—25 thereof.

Referring more particularly to the drawings, the machine illustrated comprises a base or main frame 10, Figs. 1 and 2, carrying a series of support pedestals 11, 12, 13 and 14. At the forward end of the base there is supported a rotatable

forming head, generally indicated by the numeral 15 in Figs. 1, 2, 3 and 4 which carries and within which the forming tool is operative for forming and shaping the work piece. The forming head comprises a casting or head frame member 16, Fig. 4, and a radially outwardly extending portion 17, Figs. 3 and 8, of generally circular and plate-like form. As best shown in Fig. 8, the radially extending portion 17 of the head frame

terminates in an outer cylindrical flange 18, and is also provided with a pair of diametrically extending track portions within which the operating parts for the forming tool are radially reciprocable. These track portions are U-shaped in cross section. As best shown in Fig. 8, the track

55

portion which is uppermost in the particular position of the rotatable head illustrated in the drawings comprises a pair of side walls 19 and 20, and a rear wall 21. Similarly the diametrically opposite track portion comprises side walls 22 and 23, and a rear wall 24, as best shown in Fig. 5. See also Figs. 3 and 4.

A tool carrier 27, Figs. 3, 4 and 9, is provided with a pair of diametrically opposite extensions 28 and 29 radially shiftable within the two diametrically opposite U-shaped track structures. The tool carrier is adapted to support in press-fitted relation the outer race of a ball bearing 30, the inner race of which in turn supports the forming tool 31. The forming tool is in the form of an annular ring, and is provided on its inner periphery with annular cam formations 32 in accordance with the particular shaping to be imparted to the work pieces. The forming tool is held in place by an annular lip 33, Fig. 9, formed thereon and by a clamp plate 34 held in place by a series of screws 35 adapted to be received within threaded openings 36 in the forming tool. The lip or flange 33 and the clamp plate 34 embrace opposite faces of the inner race of the ball bearing, whereby to hold the forming tool in position within the tool carrier 27. It will be seen that whereas the tool carrier 27 rotates with and at the speed of the head frame, the forming tool itself is independently rotatable at a speed determined by its contact with the work piece, due to the provision of the bearing 30.

Means is provided for diametrically shifting the tool carrier 27 whereby to shift the forming tool radially in its operation upon the work piece. This means comprises a bell-crank 38, Fig. 4, pivotally mounted on a shaft 39 carried by a pair of ears 40 and 41, Fig. 8, forming a part of the head frame plate. A U-shaped slide 42, Figs. 3, 4 and 8, is adapted for reciprocation within the head frame track 19, 20, 21, this slide being provided with an opening or socket 43 in its rear wall adapted to receive one of the arms 44 of the bell-crank, which arm projects through an opening 45 in the rear track wall 21. The slide 42 is also provided with a threaded opening 46 adapted to receive a clamp screw 47, which clamp screw also extends through an elongated slot 48 in the extension 28 of the tool carrier 27. By means of the clamp screw 47 the tool carrier 27 and the slide 42 may be clamped firmly together for movement as a unit, the slot 48 however permitting adjustment of the tool carrier relative to the slide upon loosening of the screw. This adjustment is facilitated by means of a threaded stud 50, Fig. 4, engageable with the end of the tool carrier extension 28, which stud extends through a threaded opening in a cross bar 51 carried by the slide 42 in a pair of notches 52 and 53 formed in the side walls thereof. Upon loosening of the clamp screw 47, the adjustment stud 50 may be turned to adjustably position the tool carrier 27 and slide 42 relative to each other.

A cover plate 55 overlies the slide 42, and retains it for reciprocation within the track 19, 20, 21, this cover plate being bolted to the front edges of the track side walls by suitable means such as screws 56. The cover plate is provided with a slot 57, Fig. 8, within which the head of the clamp screw 47 reciprocates during the reciprocation of the slide. A second cover plate 58 overlies the outer end of the slide 42, this cover plate being held in position by means of screws 59, and also being provided with an opening 60

75 through which tools may be inserted to effect the adjustment of the threaded stud 50.

Similar means is provided for guiding the opposite extension 29 of the tool carrier, such means comprising a slide 62, Figs. 3, 4 and 5, reciprocable within the head frame track 22, 23, 24, which slide is adapted to be clamped to the tool carrier extension 29 by means of a clamp screw 63. A cover plate 64 held in place by screws 65 overlies the front of the slide, and a second cover plate 66 overlies the end of the slide, in a manner similar to the plate 58 previously described. This cover plate 66 is in this instance, however, provided with an opening adapted to receive a press-fitted pin 67 projecting radially inwardly, and adapted to form the guiding means for a compression spring 68 which bears against the end of the tool carrier extension 29 whereby to hold the opposite tool carrier extension 28 in engagement with the adjustment stud 50. The cover plate 64 is provided with a slot 69, Fig. 3, within which the head of the clamp screw 63 is reciprocable as in the case of the screw 47 and cover plate 55.

It will be seen that by reason of the described connections, upon operation of the bell-crank 38 corresponding reciprocating movements may be imparted to the tool carrier 27, which in turn imparts corresponding reciprocations to the forming tool 31. Adjustment of the tool carrier and tool to predetermine the range of reciprocation may be effected by manipulation of the stud 50 upon release of the screws 47 and 63.

To effect the rotation of the head frame, the sleeve 16 thereof is press-fitted onto and spline-connected with, as indicated at 72, Fig. 4, a rotatable drive sleeve 73. This drive sleeve rotates within bearings 74 and 75, Figs. 1 and 4, carried by the frame pedestals 11 and 12, and has keyed thereto a pulley 76 adapted to be driven by suitable means such as V-belts 77 powered from a source of power supply. It will be seen that as the pulley is rotated corresponding rotation is imparted to the head frame and the tool carrier 27. The pulley wheel 76 is held on the sleeve 73 by means of a nut 78, Fig. 1, a thrust bearing 79 being provided between the pulley and the base pedestal 11.

To effect actuation of the bell-crank 38, the inner end of the radially extending arm 82 thereof is adapted to be received within an opening or socket 83 formed in a sleeve 84 loosely fitted onto the sleeve 16 so as to be rotatable therewith but longitudinally slidably thereon. This sleeve 84 has a collar 85, Fig. 4, secured to its end by means of a set screw 86, a pair of ball bearings 87 and 88 being held in place upon the sleeve by this collar. The two bearings collectively grip therebetween a collar 89 provided with two diametrically extending pins 90 and 91, Figs. 1, 4 and 6. It will be seen that the arrangement is such that any longitudinal movements imparted to the collar 89 impart corresponding longitudinal increments of movement to the sleeve 84. Collar 89, however, is non-rotatable, whereas sleeve 84 rotates with sleeve 16, being so caused to rotate by means of its connection with the bell-crank 38.

The pins 90 and 91 are journaled in slots formed in the upper and lower arms 92 and 93, respectively, of a yoke member 94 pivotally mounted upon a bolt 95 journaled in a frame bracket 96 forming a part of the machine base 10. The end of the upper yoke arm 92 is provided with a slot 97, Fig. 7, adapted to receive a pivot bolt 98, which bolt also extends through an open-

ing 99 in an elongated control rod 100, Figs. 1 and 2, extending axially of the machine and journaled in bearing blocks 11a and 12a forming a part of the pedestals 11 and 12. The bolt 98 forms a pivot connection between the end of the rod 100 and the yoke arm 92. An adjustment screw 101, Fig. 1, is adapted to engage the bearing block 11a to limit the movement of the control rod 100 to the right as seen in Fig. 1, this screw being received within a threaded opening 102, Fig. 7, in an angular bent end portion of the control rod. This control rod portion is slotted as indicated at 103, and provided with a threaded opening 104 to receive a lock screw 105. The arrangement is such that the lock screw may be operated to compress the slot 103, whereby to hold the adjustable stop screw 101 in adjusted position.

The opposite end of the control rod 100 carries a split clamp bracket 107 held in position on the rod by means of a bolt 108. This bracket carries an adjustment screw 109, the head of which is adapted to engage the bearing block 12a whereby to limit the movement of the control rod 100 in its opposite direction, or to the left as seen in Fig. 1.

The end of the control rod adjacent the clamp 107 is pivotally connected by means of a pivot bolt 110, Figs. 1 and 2, to a fitting 111 provided with an integral extension in the form of an elongated bolt 112 threaded on its end and adapted to receive a nut 113. The end of the bolt 112 extends through a fitting 114 which fitting has a projection 115 extending through and pivotally connected to the end of the main control lever 116 pivotally mounted upon the frame of the machine. More specifically, referring to Fig. 21, the main control lever is pivotally mounted upon a portion 13a of the pedestal 13 by means of a pivot pin 117. A compression spring 118 embraces the elongated bolt 112 and bears at its ends against the fittings 111 and 114.

In Fig. 1 the control lever 116 is shown in its normal or neutral position, the stop screw 109 of the control shaft 100 being in abutting engagement with the bearing block 12a and the compression spring 118 substantially relaxed. It will be seen that as the control lever is shifted counterclockwise or to the position as indicated at 116a in dotted lines in Fig. 1, no motion is imparted to the control rod 100 because of the engagement already existing between the screw 109 and the bearing block 12a. During this movement of the control lever the spring 118 is merely compressed, the fitting 114 sliding on the elongated bolt 112. However, when the main control lever is shifted clockwise to its dotted position as indicated at 116b, the control rod 100 will be shifted to the right as seen in Fig. 1 through an extent of travel permitted by the stop bolt 101, thereby shifting the sleeve 84, Fig. 4, to the right and operating the bell-crank 38 to shift the forming tool from an inoperative or concentric position as shown in Figs. 4 and 11, to an operated or forming position as shown in Fig. 13.

The work support or chuck for gripping the work piece, to be operated upon by the forming tool, is best shown in Figs. 4, 10 and 11 to 16 inclusive. The support chuck comprises a central mandrel 120 illustrated in perspective detail in Fig. 10. This mandrel is provided at one end with an extension 121 adapted to be arranged within the work piece 122, illustrated as a ferrule to be secured onto the end of a piece of flexible metal hose 123, Fig. 17, in the particular em-

bodiment disclosed. As best shown in Figs. 17, 18 and 19 the ferrule comprises an inner generally cylindrical portion 124 adapted to extend into the bore of the hose, an external generally cylindrical portion 125 adapted to embrace the outer periphery of the hose end, and a flange portion 126.

The ferrule is initially shaped as indicated in Fig. 17. In accordance with the principles of the invention, the ferrule is first arranged with respect to the hose end as shown in Fig. 17, and a tool 127 having a series of flutes or grooves 128 is then inserted into the inner portion 124 of the ferrule as shown in Fig. 18, while the tool is rotating, whereby to expand the inner flange into gripping engagement with the tubing wall and to form it into true cylindrical form. Any suitable apparatus may be employed, comprising means for holding the ferrule and tubing, and means for rotating the tool 127 and causing it to be inserted into the end of the ferrule while in rotatable operation. The flutes or grooves 128 facilitate the expansion of the ferrule portion 124 into gripping engagement with the tubing wall, without mutilation of the flange 126, or causing it to deviate from its original position. The grooves effect the taking of a slight cut on the portion 124 of the ferrule as the rotating tool is inserted, and as the portion 124 is expanded.

With the ferrule and tubing in the condition illustrated in Fig. 18, they are applied over the end of the mandrel projection 121, as shown in Fig. 11, the ferrule flange being brought into abutting engagement with a collar portion 130 formed on the mandrel.

A plurality of jaw members 131, three in the particular embodiment shown, also form a part of the work holding means and collectively embrace the mandrel. These jaw members, one of which is shown in perspective detail in Fig. 16, include a forward or clamping portion 132 adapted to grip the ferrule flange 126 and clamp it into engagement with the mandrel collar 130, and a rear portion 133 carrying a radially projecting pin 134. The forward edge of the clamping portion 132 of each jaw member is beveled as indicated at 135 for cooperation with a beveled or cam surface 136, Fig. 11, on the forward end of a sleeve 137 within which the jaw members are disposed. This sleeve 137 is threadedly connected as indicated at 138 to a stationary frame sleeve 139 extending longitudinally of the machine, the details of which will be later described. A bushing 140, Fig. 11, is press-fitted into the end of the rotatable drive sleeve 73, the drive sleeve with its bushing being rotatable upon the non-rotatable and fixed sleeve 137.

The end of the mandrel 120 opposite to the work support portion 121 is screw threaded as indicated at 142 whereby to have screw threaded connection with an axially shiftable chuck operating sleeve 143. The threaded end portion of the mandrel also has a kerf and slot connection with a rod 144 disposed internally of the sleeve. The structure and functions of the parts 143 and 144 will be later more particularly described, suffice to say at this point that the sleeve 143 is non-rotatable but is provided with means for causing it to shift axially, and that the rod 144 normally moves as a unit with the sleeve 143.

A still further sleeve member 146, shaped as shown in Fig. 11, is loose or floatingly mounted upon the mandrel and within the fixed sleeve 137. This floating sleeve is provided with a series of openings 147 adapted to receive the pins 134

of the jaw members. A compression spring 148 is arranged within the floating sleeve and bears at one end against the ends of the jaw members and at the other end against the floating sleeve portion or flange 149. The mandrel is provided with a rib 150 which is adapted to engage the jaw members adjacent their rear ends when the jaw members and mandrel are shifted relatively axially.

In operation, the open position of the chuck is illustrated in Fig. 11, the tubing and attached ferrule having been placed over the support portion 121 of the mandrel into engagement with the mandrel collar 130, and the gripping jaws 131 being in open or released position. Upon a forward shifting of the operating sleeve 143, the mandrel is first axially shifted forwardly relative to the gripping jaws whereby to cause the rib 150 to engage the rear portions of the jaws, moving the jaws into substantially horizontal position and causing the gripping flanges 151 thereof to be moved sufficiently radially inwardly so that they may be engaged by the ferrule flange 126. Continued forward movement of the operating sleeve 143 causes the ferrule flange to engage the gripping flanges 151, forcing the beveled surfaces 135 of the jaws into engagement with the beveled cam surface 136 of the fixed sleeve 137, as shown in Fig. 13, whereby as the operating sleeve 143 is projected forwardly, the ferrule will be tightly gripped by the chuck jaws and also held in supported relation upon the mandrel support projection 121. As the bell-crank 38, Fig. 4, is then operated, as heretofore described, the forming tool 31 is eccentrically shifted, during rotation of the head frame, and the outer cylindrical portion 125 of the ferrule is formed or shaped as indicated in Figs. 13 and 19. As the chuck operating sleeve 143 is retracted, after the forming operation, the gripping jaws of the chuck again assume the position illustrated in Fig. 11, the compression spring 148 and the openings 147 of the floating sleeve causing the jaws to pivot into and be maintained in open position as shown.

The means for shifting the chuck operating sleeve 143 is best illustrated in Figs. 1, 2, 20, 21 and 22. As shown, the stationary frame sleeve 139 projects rearwardly substantially along the entire length of the machine. The operating sleeve 143 is axially shiftable in this frame sleeve. More particularly, Fig. 21, the operating sleeve is provided adjacent its rear end with an opening adapted to receive a pin 155, the central body portion of which is oblong in cross section. This pin is provided with upper and lower threaded extensions adapted to receive nuts 156 and 157 whereby to form a pivotal connection between the pin and a pair of links 158 and 159. These links are pivotally connected at their opposite ends to a pair of pins 160 and 161, respectively, which pins are press-fitted into upper and lower plates 162 and 163 pivotally mounted upon a pin 164 by means of nuts 165 and 166.

The shape of the plates 162 and 163 is best shown in Figs. 1 and 20. They are interconnected by a pair of tie-bolts 168 and 169, whereby to hold the plates in parallel relationship, the latter tie-bolt 169 also acting as a stop to limit the clockwise shifting of the plates on the pivot 164. A spacing sleeve 170 and bolt 171, Fig. 22, also extend between the plates adjacent one end thereof, the bolt 171 having an enlarged lug or head 172 at the upper end thereof. This lug loosely receives an elongated bolt 173, Figs.

1 and 22, which, as shown in Figs. 1 and 2, is provided at one end with lock nuts 174, at its intermediate portion with a collar 175 and is threaded at its opposite end 176 into a yoke-like fitting 178 pivotally connected as indicated at 179 to the main control lever 116. A compression spring 180 embraces elongated bolt 173, bearing at one end against the lug 172 and at its opposite end against the lock nuts 174.

- 10 In operation, as the control lever 116 is swung counterclockwise or to the position 116a, as seen in Fig. 1, the collar 175 of the elongated bolt 173 causes a counterclockwise pivoting of the plates 162 and 163 whereby to draw the links 158 and 159 to the right as seen in Figs. 1, 20 and 21. This movement of the links causes the pin 155 to correspondingly move to the right thus drawing the chuck operating sleeve 143 to the right, into the position shown in Fig. 11, whereby to open the work-supporting chuck and jaws, permitting insertion of the work piece. A restoring of the control lever 116 to its neutral or full line position of Fig. 1 causes the operating sleeve 143 to be restored or shifted to the left into the position shown in Fig. 13 whereby to cause the chuck jaws to grip the work piece, as shown. Further clockwise movement of the control lever 116 into the dotted line position 116b shown in Fig. 1 merely results in a compression 30 of the spring 180, further clockwise shifting of the plates 162 and 163 being prevented by the stop pin 169. To permit the shifting of the oblong pin 155, the stationary frame sleeve 139 is provided with elongated slots 181 and 182, 35 Figs. 21. This portion of the frame sleeve is also provided with flat upper and lower surfaces 183 and 184, Fig. 22, whereby to accommodate the movement of the links 158 and 159.
- Means is provided for adjusting the position 40 of the pivot pin 164, whereby to adjustably determine the limits of movement of the chuck operating sleeve 143. More particularly, the central body portion of the pin 164 is oval in cross section. It is slidably adjustable in slots 45 186 and 187 provided in the fixed frame sleeve 139, and is carried within an opening provided in the end of an adjustment shaft 188, Fig. 21, adjustably slidable within the frame sleeve. The opposite end of this adjustment shaft 188 carries a pin 189, Figs. 21 and 24, also adjustably 50 slidable in the frame sleeve, by means of slots 190 and 191. The ends of this pin project into an internal annular channel 192, Fig. 20, provided in a rotatable collar 193 threadedly adjustable on the threaded end portion 194 of the fixed frame sleeve. A lock nut 195 is provided for holding the collar 193 in adjusted position. It will be seen that by rotation of the collar 193 in one direction or the other upon the threaded 55 end portion 194 of the frame sleeve, the adjustment shaft 188 and the pin 164 will be longitudinally shifted to adjust the limits of travel of the chuck operating sleeve 143. As stated, the lock nut 195 holds the adjustment collar 193 in 60 adjusted position.

- Means is also provided for adjusting the position of the frame sleeve 139 whereby to bodily position the work support and chuck, relative to the forming tool 31. This adjustment means 70 comprises a rotatable nut or collar 197 internally threaded for threaded engagement with the end 194 of the frame sleeve. The collar or nut 197 is provided with an annular channel 198, Fig. 20. As best shown in Fig. 25, this channel is adapted 75 to slidably receive an arcuate clamp plate 199

mounted on the end of a threaded screw 200 supported by the main frame pedestal 14, and provided with a lock nut 201. When the screw 200 is slightly retracted the clamp plate 199 is loosely slidable in the channel 198 whereby the adjustment collar 197 may be rotated. Due to the connection between the clamp plate 199 and the channel 198, the screw 197 is prevented from axial shifting upon rotation, and accordingly an axial adjustment is imparted to the threaded end of the frame sleeve 194, as required. The bolt 200 may then be advanced to bring the clamp plate 199 into tight engagement with the collar 197, to hold it in adjusted position, and the lock nut 201 applied.

After adjustment, the frame sleeve is firmly held in adjusted position by means of a lock screw 202, Figs. 20 and 21, the end of which projects into a key-way 203, and an associated lock nut 204.

To permit replacement and substitution of the chuck mandrel, it will be seen that the end thereof is provided with a wrench socket as indicated at 205 in Fig. 10. The shaft 144, previously mentioned, disposed within the operating sleeve 143 is provided with a series of circumferentially arranged grooves 206, Figs. 21 and 23. A cylindrical pin 207 is adapted to interfit with any one of these grooves, and is normally held in position in one thereof by the end of an adjustment screw 208 provided with a lock nut 209. This adjustment screw 208 is threadedly adjustable in an oblong block 210 connected to the operating sleeve 143 by a series of screws 211, and slidable in an elongated slot 212 provided in the stationary frame sleeve 139. It will be seen that the block 210 slides within the slot 212 during axial shifting of the operating sleeve 143, but at the same time prevents inadvertent rotation of the operating sleeve relative to the frame sleeve. The shaft or rod 144 is normally bodily axially shiftable with the operating sleeve 143 being clamped in position within the operating sleeve by means of the screw 208. However, upon retraction of the screw the rod 144 is released for rotational adjustment, thus permitting the mandrel 120 to be rotated by insertion of a wrench into the socket 205, the mandrel thereby being threadedly removable from the end of the operating sleeve 143. When the screw 208 is in operative position, as shown in Figs. 21 and 23, rod 144 is prevented from rotation thereby precluding rotation and removal of the chuck mandrel 120. A compression spring 215, Fig. 21, bearing at one end against the end of the rod 144 and at its other end against pin 155, normally holds the end of rod 144 in engagement with the end of the mandrel.

It is believed that the operation is clear from the description heretofore given. Upon application of a suitable source of power to the belts 77, the head frame 15 and the tool support 27 are continuously rotated. As the main control handle 116 is shifted from its neutral position to the position indicated at 116a in Fig. 1, the work supporting chuck is opened permitting insertion of the work piece 122. During this shifting of the main control handle no motion is imparted to the control rod 100, the spring 118 being merely compressed. As the control handle 116 is restored to its neutral full line position in Fig. 1, the work piece is firmly gripped and held in proper position by the support chuck. As the control handle 116 is then shifted clockwise

to its position 116b in Fig. 1, motion is imparted to the control rod 100 whereby to shift the forming tool 31 to its eccentric Fig. 13 position to effect the forming operation upon the work piece. During this movement of the control lever or handle, the spring 180 is compressed, the work supporting chuck remaining in work piece gripping position. The forming tool rotates only so fast as required by its engagement with the work piece, in rolling contact. The axis of the rotating tool however during the forming operation, revolves within the rotatable head frame and in an increasing spiral orbit as the control rod 100 is shifted, causing contact between the work piece and the forming tool in a correspondingly decreasing spiral. It is obvious that various types of band-like or cylindrical articles may be formed or shaped, in accordance with the particular forming tool being used.

During the forming operation the work piece is properly held, against rotation, and in condition for contact with the forming tool, by the work supporting means. This work supporting means comprises the mandrel projection 121 disposed internally of the work and the gripping jaws 131 which with the mandrel collar 130 grip opposite faces of the work piece flange 126. The work support is actuated by the same control handle utilized for effecting the shifting of the forming tool.

It is obvious that various changes may be made in the specific embodiment and method steps described without departing from the spirit of the invention. The invention is accordingly not to be limited to the particular embodiments disclosed but only as indicated in the claims.

The invention is hereby claimed as follows:

1. An apparatus for attaching ferrules to hose and the like comprising means for supporting the hose end and ferrule in predetermined relation, said support means including a non-rotatable mandrel adapted to project internally of the ferrule and hose end, an annular forming tool having an annular work surface arranged to embrace the ferrule, a rotating head on which the forming tool is mounted, power means for rotating the head, and means shiftable axially of said head and including a bell crank pivoted on said head for radially shifting the forming tool relative to the head during head rotation whereby to shift the forming tool and ferrule relative to each other to cause said work surface to progressively deform an annular portion of the ferrule onto the hose in a spiral of decreasing size.

2. The method of attaching a ferrule to the end of a hose or the like which comprises expanding an inner substantially cylindrical portion of the ferrule radially outwardly into engagement with the hose wall while simultaneously effecting a light scrape cutting action on said cylindrical portion, and thereafter contracting an outer substantially cylindrical portion of the ferrule onto the hose wall.

3. An apparatus for forming band-like articles comprising non-rotatable support means engageable with the article adjacent the forming station, said means including a mandrel adapted to project internally of the article in supporting relation therewith, a forming tool, means for shifting the forming tool circumferentially and radially of the article to impart an annular configuration thereto, a support for the mandrel, and means extending axially in respect to the mandrel for locking the mandrel upon its support.

4. An apparatus for forming band-like articles comprising non-rotatable support means engageable with the article adjacent the forming station, an annular forming tool having an annular work surface arranged to embrace the article, a rotatable head in which the forming tool is mounted, support means for the forming tool shiftable radially of the head, means for adjusting the forming tool relative to its support means, and control means for shifting said tool support means radially of the head during head rotation whereby to shift the forming tool and article relative to each other to cause said work surface to progressively deform the article circumferentially in a spiral of varying size, said control means including a lever interconnecting said support means and a sleeve member shiftable axially relative to said head.

5. An apparatus for forming band-like articles comprising means for supporting the article internally adjacent the forming station, an annular forming tool having an annular work surface arranged to embrace the article, and means including a rotatable power driven member and a control member slidable axially thereof for shifting the forming tool and article relative to each other circumferentially and simultaneously radially to cause said work surface to progressively deform the article circumferentially to impart an annular configuration thereto.

6. An apparatus for forming band-like articles comprising support means engageable with the article adjacent the forming station, said means comprising a pair of cooperable clamping members adapted to be shifted relatively toward each other to clamp the article therebetween, an annular forming tool having an annular work surface arranged to embrace the article, means for shifting the forming tool and article relative to each other circumferentially to cause said work surface to progressively deform the article circumferentially to impart an annular configuration thereto, and means extending axially in respect to the article for controlling the cooperable clamping members.

7. An apparatus for forming band-like articles comprising means for fixedly supporting the article internally adjacent the forming station, an annular forming tool having an annular work surface arranged to embrace the article, a rotatable head for carrying the forming tool, power means including a drive shaft for rotating the head, and means slidable axially of said shaft for shifting the forming tool radially of the head during head rotation, whereby to shift the forming tool relative to the article to cause said work surface to progressively form the article circumferentially in a spiral of varying size.

8. An apparatus for forming band-like articles comprising means including a shiftable clamp member for supporting the article, a forming tool, and a single control member selectively operable from a neutral position to a plurality of operating positions to control the shiftable clamp member and the shifting of the forming tool and article relative to each other circumferentially to progressively deform the article circumferentially to impart an annular configuration thereto.

9. An apparatus for forming band-like articles comprising shiftable means for supporting the article, an annular forming tool having an annular work surface arranged to embrace the article, a rotating head upon which the forming tool is mounted, and means comprising a single

control member selectively operable from a neutral position to a plurality of operating positions for controlling the supporting means and for shifting the forming tool radially of the head whereby to shift the forming tool and article relative to each other to cause said work surface to progressively deform the article circumferentially in a spiral of varying size.

10. An apparatus for forming band-like articles comprising means including a shiftable clamp member for supporting the article, a forming tool, a single control member selectively operable from a neutral position to a plurality of operating positions for controlling the shiftable clamp member and the relative positioning of the forming tool and article, control mechanism between the control member and said clamp member operable by movement of the control member to one operating position for shifting the clamp member into article clamping position, and control mechanism between said forming tool and said control member operable by movement of the control member to another operating position for shifting the forming tool and the clamped article relative to each other to progressively deform the article circumferentially whereby to impart an annular configuration thereto.

11. An apparatus as claimed in claim 10, wherein both the control mechanism for the clamp member and the forming tool include means selectively operable in response to the direction of movement of said control member for alternately preventing the operation of the forming tool or the clamp member during operation of the other.

12. An apparatus as claimed in claim 11, wherein the means preventing operation of the forming tool or the clamp member includes spring means in each control mechanism operating to return the single control member to its neutral position.

13. An apparatus as claimed in claim 10, wherein the control mechanism for the forming tool includes a pivoted lever connected to a sleeve rotatable with the forming tool and operating under the influence of said control member to shift said sleeve axially of the forming tool for effecting the required relative positioning thereof with respect to the article.

14. An apparatus as claimed in claim 10, wherein the control mechanism for the clamp member includes an articulated link and lever system having one end of the system pivoted to a fixed part of the apparatus and having the opposite end thereof pivoted to a control sleeve connected to the clamp member.

15. An apparatus as claimed in claim 14, wherein the articulated link and lever system includes pairs of opposed plates pivoted to an interposed frame element.

16. An apparatus for forming band-like articles comprising shiftable means for supporting the article, an annular forming tool having an annular work surface arranged to embrace the article, a rotatable head upon which the forming tool is mounted, said head including an axially extending hub portion, a single control member selectively operable from a neutral position to a plurality of operating positions for controlling the supporting means and the shifting of the forming tool radially of the head, a sleeve mounted on said hub portion for rotation therewith and for axial movement relative thereto, lever means pivoted to a fixed part of the apparatus and engaging said sleeve but without rotation therewith, a link connected to the free end of said lever and to said control member and effective to

shift said sleeve axially of said hub portion, and means connecting said sleeve to said forming tool for shifting the forming tool radially of the head whereby to shift the forming tool and article relative to each other to cause said work surface to progressively deform the article circumferentially in a spiral of varying size.

17. An apparatus as claimed in claim 16, wherein there is provided control mechanism including lever mechanism between said control member and the supporting means for shifting and maintaining the supporting means in article supporting position.

JOHN F. P. FARRAR.
